COMPARTMENTED TRAY OR SIMILAR ARTICLE

George E. Vanden Bosch, Buchanan, Mich.

Application June 29, 1954, Serial No. 31,230

Term of patent 14 years

(Cl. D44—30)

Fig. 1

Fig. 2

Fig. 3

To all whom it may concern:

Be it known that I, George E. Vanden Bosch, a citizen of the United States of America, residing at Indian Springs Park, Buchanan, Michigan, have invented a new, original, and ornamental Design for a Compartmented Tray or Similar Article, of which the following is a specification, reference being had to the accompanying drawing, forming a part hereof, in which—

I claim:

The ornamental design for a compartmented tray or similar article, as shown.
